UNITED STATES PATENT OFFICE.

WILLIAM F. SMITH, OF SAN FRANCISCO, CALIFORNIA.

DESIGN FOR A NECKTIE-RETAINER.

SPECIFICATION forming part of Design No. 26,727, dated March 9, 1897.

Application filed January 29, 1897. Serial No. 621,247. Term of patent 7 years.

To all whom it may concern:

Be it known that I, WILLIAM F. SMITH, a citizen of the United States, residing in the city and county of San Francisco and State 5 of California, have invented and produced a new and original Design for Necktie-Retainers, of which the following is a specification, reference being had to the accompanying drawings.

Figure 1 of the said drawings is a perspective view of a necktie-retainer embodying my design. Fig. 2 is a side view of the same, taken from the left-hand side of Fig. 1. Fig. 3 is an elevation taken from the rear, or the 15 left-hand side of Fig. 2, these views being deemed necessary to fully illustrate my design.

The leading features of my design consist in a double fold or bend resembling in form 20 when viewed from the side a flattened letter S, with the limbs or members standing vertically and extending above and below the loops. The upwardly-extending member is bent or shaped at the upper end portion in a 25 sharp curve or reëntering angle, forming a rib or angular projection on that face of the

limb which is next to the top loop or bend of the body, while the lower or opposite straight limb or member is bent or shaped into a rounded or convex form on the outer face, with the 30 perpendicular edges of the limb turned backward on a curve, the convexity being disposed lengthwise of the said limb.

A is the body hereinbefore referred to. A' 35 A² are the bends or loops at the top and bottom. B is the upwardly-extending limb or member, and C is the lower or oppositely-extending limb.

B' is the angular projection on the limb B. C' is the convex surface on the lower member, 40 and C² are the backwardly-turned edges.

Having thus fully described my invention, what I claim, and desire to secure by Letters Patent, is—

The design for a necktie-retainer, substantially as herein shown and described. 45

In testimony that I claim the foregoing I have hereunto set my hand and seal.

WILLIAM F. SMITH. [L. S.]
